UNITED STATES PATENT OFFICE.

HOMER L. BRETSCH, OF HASTINGS-UPON-HUDSON, NEW YORK.

TELLURIAN.

1,099,014.

Specification of Letters Patent.

Patented June 2, 1914.

Application filed December 11, 1912. Serial No. 736,183.

To all whom it may concern:

Be it known that I, HOMER L. BRETSCH, a citizen of the United States, residing at Hastings-upon-Hudson, in the county of Westchester and State of New York, have invented new and useful Improvements in Tellurians, of which the following is a specification.

This invention relates to tellurians of the type disclosed in my prior Patent #1010226, dated November 28, 1911, and the object of the present invention is to provide certain improvements upon the device covered thereby, as hereinafter fully described and claimed.

In the accompanying drawings,—Figure 1 is a side elevation. Fig. 2 is a top plan view. Fig. 3 is a vertical longitudinal section. Fig. 4 is a horizontal section on the line 4—4 of Fig. 3. Fig. 5 is a detail vertical sectional view on the line 5—5 of Fig. 1. Fig. 6 is a bottom plan view of the axis quadrant. Fig. 7 is a detail section on line 7—7 of Fig. 3.

Referring more particularly to the drawings, 1 represents a base having any suitable outlines, but preferably circular in form. On the upper surface of the base, adjacent the periphery thereof, is spaced suitable indicia 3 and 4 indicating the months of the year and the signs of the zodiac, and also lines 5 and 6 indicating the time in which the earth passes through the solstices and equinoxes, the months of the year being arranged anti-clockwise. The center of the base is provided with the frustum of a cone 7 through which and through the base extends a shaft 8 upon which is journaled a globe supporting arm 9, the same being held down upon the cone by a conical washer 10 secured to the shaft. Said globe supporting arm is provided with a pointer 11 adapted to operate over the face of the base. The free end of the arm 9 is supported by means of a roller 12 operating over the base and carried by a bracket 13 secured to the under side of the arm. The arm 9 is preferably hollow and has inclosed therein bearing members 14, 15 and 16 in which is journaled a transmission shaft 17 having pinions 18 and 19 secured upon opposite ends thereof. The pinion 18 is in mesh with a beveled gear 20 secured to the top of the cone, and the pinion 19 is in mesh with a similar beveled gear 21 mounted upon the shaft 22 extending vertically from the arm and car-

rying upon its upper end an axis quadrant 23. The bearing 14 is in the form of a yoke bracket carried by an adjusting wing screw 14^a swiveled thereto and working in a threaded opening in the arm 9, said bracket being movable upwardly into a recess 14^b in the under side of the arm, whereby the gear 18 may be adjusted into and out of engagement with the gear 20. By this means the arm 9 may be revolved upon the shaft 8 with or without operating the shaft 17 and transmitting motion to the quadrant arm and globe, as hereinafter described.

The quadrant 23 is provided with a longitudinal series of threaded openings 24 to adjustably receive the lower end of the axle 25, said axle having a collar 26 which seats upon the top of the quadrant and a nut 27 co-operating with the washer to clamp it in adjusted position on the quadrant. By this construction the axle 25 may be mounted at different angles upon the quadrant, which latter is graduated as shown at 28, to determine the angle of the axle. Supported by the axle is an ordinary globe 29 representing the earth and having the different zones marked thereon.

Surrounding the axle 25 and secured to the under side of the globe is a gear 30 which is in mesh with a gear 31 carried upon a transmission shaft 32 journaled and pivotally mounted in a bearing opening 33 in the quadrant. The lower end of the shaft is provided with a beveled gear 34 which is in mesh with a similar but larger gear 35 held stationary upon the arm 9 and surrounding the shaft 22. Thus it will be noticed that as the arm 9 is rotated upon the shaft 8, when the pinion 18 is in engagement with the gear 20, said pinion 18 will be rotated by engagement with said gear 20 and thus, through the shaft 17, pinion 19 and gear 21 the shaft 22 will be rotated. Thus as the arm is rotated the earth will be revolved with the quadrant, and the gear 34 being in mesh with the gear 35 which is stationary upon the arm, the earth will be rotated upon its axis. It will, however, be apparent that by adjusting the screw 14^a to throw the gear 18 out of mesh with the pinion 20, the arm 9 may be revolved upon its axis without transmitting motion to the shaft 17, and therefore without rotating the shaft 22 and quadrant 23. The shaft 22 carries an arm 22^a having its free end arranged at an angle thereto and provided with a longitudi-

- nal slot 22^b. Slidably engaging said arm 22^a is a sleeve 32^a having openings in its top and bottom for the passage of the shaft 32, which also extends through the slot 22^b. The inner end of the sleeve is provided with a longitudinally slotted extension 32^b adjustably secured to the arm 22^a by a set screw 32^c. By this construction the sleeve may be adjusted on the arm 22^a to shift the shaft 32^b so as to throw the gear 34 into and out of mesh with the gear 35, whereby the arm 9 may also be revolved with or without turning the shaft 32 and rotating the globe upon its axis 25.
- 15 In order that the circle of illumination and the twilight belt may be clearly shown upon the globe during all periods and at all places, there is secured to the arm 9 a standard 36 from which projects a horizontal yoke member 37 surrounding one-half of the globe and having secured to its outer ends a substantially semi-circular bar 38 which is of sufficient size to permit the passage of the globe in all of its positions.
- 20 Spaced from the bar 38 is a similar bar 39 which has its ends stepped in the supporting member 37 and is connected to the bar 38 by a bridge piece 40 which has its outer end threaded and passed through the member 38 and provided with a thumb nut 41, so that the member 39 is spaced away from the member 38 a distance corresponding to 18° upon the globe, which is the width of the twilight belt.
- 25 Mounted upon the end of the shaft 8, which is hollow, is an electric globe 42 having a connection with a source of current supply by wires 43 which extend through the shaft, and a pipe 44 is also connected to the shaft so that the sun may be represented by a gas globe instead of an electric incandescent light. The hollow shaft 8 is provided with an offset portion 8^a, arranged to change the position of the light with respect to the globe 29 at different positions in the movements of the arm 9 to illustrate the perihelion and aphelion, in the months of December and June, respectively, or that the earth is nearer the sun in winter than in summer. In order that the position of the vertical rays may be indicated upon the globe, a standard 45 is secured to the arm intermediate its length and mounted upon

the upper end of the standard is a thin arm or pointer 46 which is in line with the sun and the 90° mark on the quadrant or with the intermediate point between the poles. By rotating the arm anti-clockwise over the base the before mentioned results may be readily determined.

I claim:—

1. In a device of the class described, the combination with a base, of an arm rotatably mounted thereon, a quadrant, means actuated in the rotation of the arm for rotating the quadrant, means for throwing the first named means into or out of action, a shaft mounted upon the quadrant, and a globe rotatably mounted upon the shaft.

2. In a device of the class described, a base, an arm rotatably mounted thereon, a quadrant, a shaft carried thereby, a globe rotatably mounted upon the shaft, gearing actuated by the rotation of the arm for rotating the quadrant, means for throwing said gearing into and out of operation, gearing actuated by the first named gearing in the rotation of the arm for rotating the globe upon its shaft, and means for throwing the latter named gearing into and out of action.

3. In a device of the class described, a base, an arm rotatably mounted thereon, a shaft carried by the arm and journaled in the base, a gear surrounding said shaft and fixed to the base, a gear rotatably mounted in the arm, an operating connection between the gear on the base and the last named gear, means for throwing said connection into and out of operation, a quadrant secured to the gear rotatably mounted in the arm, a shaft carried by said quadrant, a globe mounted upon the shaft, a gear secured to the arm, a gear secured to the globe, a shaft rotatably and pivotally mounted on the quadrant and provided with gears meshing with said gears on the globe and arm, and adjusting means coupled to said shaft for pivotally moving the same to throw the last named gears into or out of action.

In testimony whereof I affix my signature in presence of two witnesses.

HOMER L. BRETSCH.
